UNITED STATES PATENT OFFICE

JULIAN L. PERKINS, OF WEST SPRINGFIELD, MASSACHUSETTS

WRINGER

Application filed April 6, 1931. Serial No. 528,092.

This invention relates to improvements in wringers and is directed to safety wringers so-called. The invention has for its particular object the provision of a wringer for use in connection with a washing machine or the like which has incorporated therewith certain novel features of construction whereby an operator may easily and readily disconnect certain operating parts.

According to special features of the invention the wringer is so constructed and arranged that an operator may easily and readily take advantage of the safety features. In fact an operator may quite unconsciously and involuntarily disengage and move certain parts to an inoperable position thereby safeguarding against personal injury.

Various novel features and advantages of the invention will be hereinafter more fully referred to in connection with the accompanying description of the preferred form of the invention, the same being illustrated in the accompanying drawings, wherein:

Fig. 1 is a partial front elevational view taken at one side of the wringer with said parts in section for clearness.

Fig. 2 is a plan view of the parts shown in Fig. 1.

Fig. 3 is an elevational sectional view on the line 3—3 of Fig. 1.

Fig. 4 is a small scale transverse sectional view through the wringer showing the parts in a neutral position.

Fig. 5 is a small scale front elevational view of a wringer embodying the novel features of the invention.

Fig. 6 is a view similar to that of Fig. 4, with the parts in what may be called a forward position.

Fig. 7 is a similar view showing the parts in a reverse position.

Fig. 8 is a view similar to that of Fig. 1 showing a modified form of the invention.

Fig. 9 is a plan view of the parts shown in Fig. 8.

Fig. 10 is a sectional elevational view on the line 10—10 of Fig. 8.

Fig. 11 is a view similar to that of Fig. 1,

showing another modified form of the invention.

Fig. 12 is a plan view of the parts shown in Fig. 11, taken on the line 12—12 of Fig. 11, and

Fig. 13 is an elevational sectional view taken on the line 13—13 of Fig. 11.

Referring now to the drawings in detail the invention will be more fully described.

In describing the invention reference will be made to a frame, one form of which is shown in Fig. 5. This may have an upper cross member 2 and side supports 4. The wringer frame may take any usual form and that shown and to be described is merely for illustrative purposes. In describing the invention reference will be made to a wringer head H which may be supported by and operatively connected to a shaft of a washing machine or other device.

In Fig. 1, the head H includes a housing 6 which in some suitable manner is supported by a tube 8. This is adapted for connecting to a suitable support and a drive shaft 10 is journalled in the housing at its lower end for connecting to a suitable source of power. The shaft 10 may be continuously operated while the wringer may be connected thereto so that the rolls thereof may rotate in opposite directions or disengaged entirely from the driving shaft 10, as will appear.

A driving pinion 12 is carried by the upper end of the shaft 10. A barrel 14 is slidable and oscillatable in the housing 6 and is suitably fixed as by welding or by screws such as 18 to one of the members 4 of the wringer frame, so that the wringer frame and barrel may reciprocate and oscillate together relative to the housing.

A shaft 20 preferably in the form of a tube has its outer end 22 rotatably and reciprocably mounted in a bearing 7 of the housing while its inner end 23 is rotatable in the barrel 14. A pair of gears 24 and 25 are fixed to the shaft 20 and as the shaft is moved in one direction or the other, either one of the gears is brought into mesh with the driving pinion 12 whereby the shaft 10

will drive the shaft 20 in one direction or the other.

A driving roll 30 has a shaft 32 thereof suitably journaled in a support 4 at the 6 left-hand side of the frame, while its right-hand end extends through a part 34 within the barrel 14. Its extremity extends into and is fixed to the tubular shaft 20 by means of a pin or the like 36.

10 As the wringer frame is moved from left to right, it will be apparent that the barrel 16 is moved thereby and that this in turn moves the shaft 20 and gears back and forth for meshing with the pinion 12.

15 A pin 40 is carried by the barrel 14 and extends upwardly therefrom into a slot 42 in the upper side of the housing, as is shown clearly in Fig. 2.

20 The central part of the slot 42 is disposed angularly with respect to the axis of rotation of the shaft 32 and has end portions 44 in offset parallelism which are disposed transversely to said axis. It will be readily obvious that if the frame of the wringer 25 is tipped forward or back that the pin 40 will travel along the slot and move the barrel and consequently the gears 24 and 25 relative to the driving pinion 12 so that one of the gears is brought into mesh with the driving pinion 12.

30 The parts are shown in Figs. 1 and 2 in a neutral position wherein the frame assumes a normal vertical position as shown in Fig. 4. In this position neither of the 35 gears are in mesh with the driving pinion whereby the driving roll 30 is not connected for rotation.

35 A lock which may be in the form of a ball 50 is spring pressed upwardly by a 40 spring 52 in a bore 54 at the lower side of the housing and co-operates with an opening 56 in the lower side of the barrel so that the barrel and consequently the wringer frame are yieldingly held in the neutral position referred to.

45 An apron 60 is carried by the wringer frame, beneath roll 30 and has side portions 62 and 64 for underlying clothes fed to the rolls. A driven roll 66 for contacting with the driving roll has a shaft 67 suitably journaled in the supports 4 of the wringer frame.

50 In the operation of the wringer it will be assumed that the operator is to stand at the 55 right-hand side of the wringer as is shown in Fig. 4. In this case it may be desired to feed the clothes forwardly between the rolls and from the operator in the direction of the arrow F, as shown in Figs. 4 and 6. In this 60 case the operator may move the frame to the left and this may be done by grasping the frame or the apron 64 so as to move the wringer frame to the position shown in Fig. 6. This movement of the frame will rotate 65 the barrel 14 so that by means of the pin and

slot the frame and housing will be moved longitudinally of the housing and bring one of the driven gears into mesh with the driving pinion 12.

The shaft 10 may be rotated so that in 70 this position the wringer rolls will be rotated in the direction of the arrows shown in Fig. 6.

With the parts in the position shown in Fig. 6, the clothes may be fed forwardly 75 through the rolls. In case it is desired to instantly stop the rolls or to rotate the rolls in a reverse direction, the operator has but to press on the apron 64 or pull on the frame in order to swing the wringer to the 80 neutral position shown in Fig. 4 or to the reverse position shown in Fig. 7.

Frequently an operator's hand or clothing 85 becomes caught between the rolls in the feeding of the clothes therethrough and it is therefore to obviate this danger that this safety feature of this invention is directed.

As stated, the operator need only bear on or against the apron 64 either with an arm or the body so as to cause the frame to 90 swing to the upright neutral position or to the reverse position shown in Fig. 7. As the frame is thus swung the barrel is moved so as to disengage one of the gears or the one which is in mesh with the driving pinion, and thereby disconnect the driving roll from the shaft 10. With sufficient pressure on the apron 64 the frame may be swung past its neutral position to engage the other of the gears and cause the rolls to operate 100 in an opposite position. In either event forward feeding movements of the rolls are arrested.

105 It will be observed that the operator may stand at either side of the wringer and by pressing on the apron disposed between the operator and the wringer it will be possible to move the wringer from an operative clothes feeding position to a neutral or reverse non-feeding position. The operator is safeguarded against injury and the parts are so constructed and arranged that the operator may involuntarily bring the safety feature into play.

110 The modification of the invention shown in Figs. 8, 9 and 10 will now be described.

In this form of the invention a housing 70 is provided which is similar to that already described and as in the former case a shaft 72 is rotatable therein which carries a driving pinion 74.

115 A barrel 76 is associated with a sleeve 78 which is reciprocable and oscillatable in the housing. The sleeve is fixed to an end support 79 of a wringer frame and a driving roll 80 has a shaft 82 rotatable in the barrel 76 with its outer end rotatable and reciprocable in the housing. Gears 84 and 86 are fixed in spaced relation on the shaft 82 and are arranged to engage with the pinion 74. 120 125 130

The shaft 82, gears 84 and 86, parts 76, 78 and 79 are shiftable as a unit endwise of the housing.

A driven roll 90 has a shaft 91 suitably 5 journalled between end frames such as 79 and is adapted to contact with the driving roll 80.

A collar 92 is arranged for oscillating movements on the housing 70 and has radi ally disposed arms 94 extending therefrom. Bars 96 extend from the arms at either side of the frame and may have their left-hand ends joined together or suitably connected to a part. These bars are preferably disposed so as to lie between the operator and the wringer whether the operator is at one side or the other of the wringer.

A pin 100 carried by the barrel 76 works in a longitudinal slot 102 of the housing and 20 has its upper end in a slot 104 on the inner periphery of the collar 22. This slot 104 is angularly disposed as shown in Fig. 9 so that as the collar 92 is rotated the pin will be moved back and forth along the slot 102 25 and thereby move the barrel 76 and gears 84 and 86 longitudinally of the housing and bring either one or the other of the gears 84 and 86 into mesh with the pinion 74.

The operator may grasp one of the rods 30 96 and this will depend of course upon which side of the wringer the operator is positioned. By moving one of the bars 96 it is possible to rotate the collar 92 and thereby move one of the driven gears from 35 engagement with the gear 74 and either bring the gears to an inoperative position or engage the other gear for rotating the rolls in an opposite position.

As in the former case the operator will 40 involuntarily grasp a rod 96 and move the gears so as to either stop rotation of the rolls entirely or reverse them and in that way safeguard herself against injury.

The modification of the invention shown 45 in Figures 11, 12 and 13 will now be described in detail.

In this case a support 110 of a wringer frame similar to that already described is provided and has rotatable therein a shaft 50 112 of a lower driving roll 113 and a shaft 114 of an upper driven roll 115. A barrel 116 has a flange portion 118 fixed to the frame 110. Suitably spaced gears 118 and 120 are carried by the shaft 112 and are 55 arranged to mesh with a driving pinion 122 associated with a housing 117 so that either one of the gears 118 and 120 may be rotated to thereby rotate shaft 112 in one direction or the other. The barrel 116 is rotatable and reciprocable in the housing 117 60 which encloses the gears.

Lugs 130 extending forwardly from the flange 118 have rolls 132 which work on inclined faces of upper and lower cams 136 65 and 138 carried by the housing. These cams

are arranged so that as the frame is swung in one direction or the other it will be moved back and forth relative to the housing so as to carry the gears 118 or 120 into and out of mesh with the driving pinion 122.

In this case the operator may stand at either side of the wringer for feeding clothes forwardly between the bite of the roll 113 and 70 115. In order to rotate the rolls in the desired direction for wringing clothes the frame is tilted by the operator. As it is tilted it will be moved in one direction or the other longitudinally so as to engage either of the driven gears with the driving pinion.

In case it is desired to stop rotation of the rolls or in the event the operator has a hand caught between the rolls, all that is necessary to do is to tilt the wringer frame in an opposite direction. A partial tilting 75 movement will of course bring it to a vertical neutral position where the gears are in inoperative relation. Additional movement will tilt the frame to bring the other of the driven gears into engagement with the driving pinion and in that case the rolls will be rotated instantly in opposite directions.

In either of the embodiments of the invention shown the operator may stand at either side of the wringer. According to the direction of rotation of the driving shaft 80 the gears may be engaged to rotate the rolls in the desired direction for receiving the clothes.

Regardless of which side of the wringer 85 the operator is located it is possible to disengage the gears altogether or to cause a reverse rotation of the wringer rolls either by tilting the wringer frame in an opposite direction or by manipulating a rod 96 to the end that the operator is safeguarded against injury. The parts are so arranged that the safety feature is brought into play quite involuntarily by the operator. It is not necessary for the operator to reach for some inconveniently located part as is the case with 90 prior art apparatus and which is quite difficult in the event that the operator has a hand caught. The construction is such that the safety operation is brought about with the least possible mental and physical effort on the part of the operator and it is not necessary to rely upon some particular unnatural effort of the operator.

The novel features and advantages of the 95 invention will be quite apparent from the foregoing and it is therefore desired to be limited, if at all, by the appended claims rather than by the foregoing description.

What is claimed is:

1. A wringer comprising in combination, 100 a support having a driving pinion associated therewith, a frame member reciprocable relative thereto, driving and driven rolls associated with said frame member and a driven 105

gear associated with said driving roll shiftable by said frame member for engaging said driving pinion accordingly as the frame member is moved in one direction or the other relative to said support.

- 5 2. A wringer comprising in combination, a support having a driving pinion associated therewith, a frame member reciprocable and oscillatable relative thereto, driving and 10 driven rolls associated with said frame member and driven gears associated with said driving roll shiftable by said frame member for alternately engaging said driving pinion accordingly as the frame member is moved 15 in one direction or the other relative to said support.

3. A wringer comprising in combination, a support having a driving pinion associated therewith, a frame member reciprocable and 20 oscillatable relative thereto, driving and driven rolls associated with said frame, driven gears associated with said driving roll and movable with the frame member to alternately engage said pinion and means 25 associated with said support and frame member whereby they are reciprocated relative to one another accordingly as they are rotated relative to one another in one direction or the other.

- 30 4. A wringer comprising in combination, a support having a driving pinion associated therewith, a frame member reciprocable and oscillatable relative to said support, means associated with said support and frame 35 member whereby relative reciprocating movements are brought about by relative oscillating movements, driving and driven rolls in said frame member, driven gears associated with said driving roll being reciprocable by the frame for alternately engaging said driving pinion.

- 45 5. A wringer comprising in combination, a support member having a driving pinion associated therewith, a frame member oscillatable and reciprocable therein, one of said members having a pin receivable in a slot of the other member arranged to bring about relative reciprocation of the parts as they 50 are oscillated relative to one another, a driving and a driven roll in said frame, spaced driven gears associated with said driving roll movable with the frame member for alternately engaging said pinion accordingly 55 as said frame member is moved in one direction or the other.

- 60 6. A wringer comprising in combination, a support having a driving pinion associated therewith, a frame oscillatable and reciprocable relative thereto, driving and driven rolls in said frame and gears movable with said frame for alternately engaging said pinion and means including a cam and a follower associated with said frame and support to bring about relative reciprocating

movements accordingly as they are oscillated relative to one another.

7. A wringer comprising in combination, a support having a driving pinion associated therewith, a frame reciprocable relative thereto, a part oscillatable relative to said support, means associated with said part and frame for reciprocating said frame as the part is oscillated, driven gears movable by said frame into and out of engagement with said pinion and a driving roll in said frame connected to said gears for operating a driven roll in said frame.

8. A wringer comprising in combination, a support, a driving element, a driving roll, a member mounted on the axis of said roll for swinging movements between operative and inoperative positions, a driven roll associated therewith and engageable connections associated with said element and driving roll adapted to be engaged and disengaged accordingly as the said member is swung on its axis between said operative and inoperative positions.

9. A wringer comprising in combination, a support, a driving element, a driving roll, engageable connections associated with said element and roll, a roll support mounted on an axis parallel to that of said roll for swinging movements between operative and inoperative positions, a driven roll in said roll support and means associated with said support for engaging and disengaging said connections accordingly as the said support is swung on its axis.

10. A wringer comprising in combination, a support, a driving element, a driving roll, engageable connections associated with said element and roll, a roll support mounted on the axis of said roll for swinging movements between operative and inoperative positions, a driven roll in said roll support and means associated with said support for engaging and disengaging said connections accordingly as the said support is swung on its axis.

11. A wringer comprising in combination, a support, a driving element, a driving roll, separate shiftable driven elements associated with said roll for alternately engaging and disengaging said driving elements, a roll support mounted on an axis parallel to that of said roll for swinging movements between a neutral inoperative and operative position, a driven roll in said roll support and means associated with said roll support for alternately shifting said driven elements into engagement with said driving element and out of engagement therewith accordingly as said support is swung into operative and inoperative positions.

12. A wringer comprising in combination, a support, a driving element, a driving roll, separate shiftable driven elements associated with said roll for alternately engag-

ing and disengaging said driving element, a roll support mounted on the axis of said roll for swinging movements between a neutral inoperative and operative position, a driven roll in said roll support and means associated with said roll support for alternatively shifting said driving elements into engagement with said driving element and out of engagement therewith accordingly as said support is swung into operative and inoperative positions.

13. A wringer comprising in combination, a support, a driving element, a driving roll, engageable connections associated with said element and roll, a roll support reciprocable in said first named support for engaging and disengaging said connections, a driven roll in said roll support, a member shiftable on said support for reciprocating said roll support to disengage and engage said connections.

14. A wringer comprising in combination, a support, a driving element, a driving roll, engageable connections associated with said element and roll, a roll support mounted on the axis of said roll for swinging movements between operative and inoperative positions, a driven roll in said roll support and means associated with said support for engaging and disengaging said connections accordingly as the said support is swung on its axis and a manually engageable part extending along said rolls.

15. A wringer comprising in combination, a support, a driving element associated therewith, a driving roll, a roll support reciprocable in said first-named support, driven elements associated with said driving roll and roll support arranged to be engaged and disengaged with said driving element accordingly as the roll support is reciprocated between operative and inoperative positions, a member oscillatable on said support, connections between said supports and member whereby the roll support is reciprocated as said member is oscillated.

16. A wringer comprising in combination, a support, a driving element, a driving roll, separate shiftable driven element associated with said roll for alternately engaging and disengaging said driving element, a roll support mounted on the axis of said roll for swinging movements between a neutral inoperative and operative position, a driven roll in said roll support and means associated with said roll support for alternately shifting said driving elements into engagement with said driving element and out of engagement therewith accordingly as said support is swung into operative and inoperative positions and a manually engageable part extending from said means along said rolls.

17. A wringer comprising in combination, support members arranged for relative

swinging movements on a certain axle between operative and inoperative positions, coacting rolls journaled in said members on axes parallel to said certain axis whereby when the members are in operative position the plane of the axes of the rolls is angular to said plane when the members are in inoperative position.

18. A wringer comprising in combination, support members arranged for relative swinging movements on a certain axis between operative and inoperative positions, coacting rolls journaled in one of said members on axes parallel to said certain axis whereby when the members are in operative position the plane of the axes of the rolls is angular to said plane when the members are in inoperative position and engageable driving connections for said rolls which are engaged and disengaged by relative movements of said members.

19. A wringer comprising in combination, support members arranged for relative swinging and reciprocating movements on a certain axis between operative and inoperative positions, coacting rolls journaled in said members on axes parallel to said certain axis whereby when the members are in operative position the plane of the axes of the rolls is angular to said plane when the members are in inoperative position.

20. A wringer comprising in combination, support members arranged for relative swinging and reciprocating movements on a certain axis between operative and inoperative positions, coacting rolls journaled in said members on axes parallel to said certain axis whereby when the members are in operative position the plane of the axes of the rolls is angular to said plane when the members are in inoperative position and engageable driving connections for one of said rolls which are engaged and disengaged by relative swinging and reciprocating movements of said members.

21. A wringer comprising in combination, support members arranged for relative swinging and reciprocating movements on a certain axis between operative and inoperative positions, coacting rolls journaled in said members on axes parallel to said certain axis whereby when the members are in operative position the plane of the axes of the rolls is angular to said plane when the members are in inoperative position and engageable driving connections for one of said rolls which are engaged and disengaged by relative swinging and reciprocating movements of said members and means associated with said support members to bring about relative reciprocating thereof as they are swung relative to one another.

22. A wringer comprising in combination, a support having a driving pinion associated therewith, a frame member reciproca-

- ble and oscillatable relative thereto, driving and driven rolls associated with said frame member and a driven gear associated with said driving roll shiftable by said frame member for engaging and disengaging said pinion accordingly as the frame member is moved in one direction or the other relative to said support.
23. A wringer comprising in combination, a support having a driving member associated therewith, a frame reciprocable relative thereto, a part oscillatable relative to said support, means associated with said part and frame for reciprocating said frame as the part is oscillated, a driven member movable by said frame into and out of engagement with said driving member and a driving roll in said frame connected to said driven member for operating a driven roll.
24. A wringer comprising in combination, a support, a pair of coacting rolls relatively shiftable between operative and inoperative positions whereby the axes of said rolls are shifted between a position where they lie in a certain plane and another position where said axes lie in a plane at an angle to said certain plane, means for holding said rolls in yielding engagement in said positions, engageable driving connections including a shiftable member which is actuated by shifting movements of said rolls.
25. A wringer apparatus comprising in combination, a support, a frame for coacting rolls oscillatable and reciprocable relative to said support, engageable driving connections for said rolls including a shiftable member which is shifted by movements of said frame and means associated with said frame and support to affect reciprocating movements of the frame as it is oscillated and vice versa.
26. A wringer comprising in combination, a relatively movable support and frame, the said frame having coacting rolls associated therewith, driving connections for said rolls including a shiftable member for engaging and disengaging the same, shifting connections between said frame and shiftable member, a member extending along said frame substantially parallel to said rolls movable towards and away therefrom whereby the frame is moved relative to the support.
27. A wringer comprising in combination, a relatively reciprocable support and frame, the said frame having coacting rolls associated therewith, driving connections for said rolls including a shiftable member for engaging and disengaging the same, shifting connections between said frame and shiftable member, a member extending along said frame substantially parallel to said rolls movable towards and away therefrom whereby the frame is moved relative to the support.
28. A wringer comprising in combination,
- a relatively movable support and frame, the said frame having coacting rolls associated therewith, driving connections for said rolls including a shiftable member for engaging and disengaging the same, shifting connections between said frame and shiftable member, and a member extending along said frame substantially parallel to said rolls movable towards and away therefrom whereby the frame is moved relative to the support.
29. A wringer comprising in combination, a support, a frame movable relative thereto, driving connections for a pair of rolls associated with said frame including a shiftable member for engaging and disengaging the same, connections between said frame and support to bring about shifting movements of the shiftable member as the frame and support are moved relative to one another and a member extending along said frame movable towards and away therefrom connected to said connections for actuating the same.
